UNITED STATES PATENT OFFICE.

HERMAN P. WILKE, OF BRAWLEY, CALIFORNIA.

PISTON RING.

Application filed October 11, 1922. Serial No. 593,832.

To all whom it may concern:

Be it known that I, HERMAN P. WILKE, a citizen of the United States, residing at Brawley, in the county of Imperial and State of California, have invented new and useful Improvements in Piston Rings, of which the following is a specification.

This invention relates to packing rings designed primarily for use on the pistons of internal combustion engines of all types and has for its object the provision of a novel piston ring which is of peculiar formation and which will operate to prevent oil from passing into the combustion chamber, thus greatly decreasing the consumption of lubricating oil and preventing fouling of the spark plugs.

An important and more specific object is the provision of a piston ring which is provided with a peripheral groove which serves to collect oil working along the cylinder walls, the groove communicating with a series of holes formed through the ring and establishing communication with the interior of the piston by means of other holes provided in the piston wall at the ring receiving groove therein.

Another object is the provision of a ring of this character in which the upper edge of the ring itself and the lower edge of the groove therein are beveled so that any oil which may have passed by the oil groove in the ring may have an opportunity to get back into the groove when the piston makes its upstroke, the other edges being of a knife-like nature and exerting a scraping action on the down stroke of the piston.

An additional object is the provision of a ring of this character which will be very simple and inexpensive in manufacture, positive in action, efficient and durable in service, and a general improvement in the art.

With the above and other objects and advantages in view, the invention consists in the details of construction to be hereinafter more fully described and claimed and illustrated in the accompanying drawings in which:—

50 Figure 1 is an edge elevation of my ring.

Figure 2 is a vertical section through the ring applied in a specially constructed piston.

55 Figure 3 is a horizontal section through the piston showing the ring in place, a portion of the ring being likewise in section.

Referring more particularly to the drawings, I have shown my ring 10 as being split in the usual manner and preferably provided with a stepped joint 11, though it is conceivable that some other type might be provided if found advantageous. The ring is also shown as being of uniform thickness throughout as this particular feature appears to be more practical.

60 The main characteristic is a groove 12 which extends throughout the periphery and which is designed for the purpose of catching oil scraped from the walls of the cylinder of the engine in which the ring is used. 70 The upper wall 13 of this groove is preferably slightly undercut at an angle, as shown, and the lower edge or wall is correspondingly beveled, as indicated at 14, the inner corner being rounded, as shown at 14^a. The 75 lower edge of the ring itself is sharp and square while the upper edge is beveled, as shown at 15.

75 The ring constructed as above described is very efficient in use without the provision of any additional features but I have found it advantageous to provide several small holes 16 which lead from the groove 12 through the inner periphery. In this event the piston A in connection with which the 80 ring is used, is formed with holes 17 which lead from the ring receiving groove B, to the interior of the piston body.

85 In actual practice it is really necessary to use only one of these specially constructed rings on each piston though of course more may be employed if preferred. In the operation it will be seen that on the down stroke of the piston the lubricating oil which has previously splashed onto the cylinder walls 90 is scraped off by the knife-like upper edge of the groove 12, the oil passing into the groove and thence through the holes 16 to the back of the ring and then through the holes 17 in the piston, and eventually 95 back into the crank case of the engine. The object of having the beveled edge 15 at the top of the ring is to avoid a sharp edge so that any of the oil which may have passed by the oil groove in the ring may have an

100 opportunity to work into the groove when the piston makes its upstroke. The peculiar design of the groove combined with the particular arrangement of sharp and beveled edges makes it practically impossible for 105 any quantity of oil to escape by the ring and pass into the combustion chamber. Oil con-

sumption is greatly reduced and fouling of the spark plugs is prevented, while the power is materially increased.

While I have shown and described the 5 preferred embodiment of my invention, it is of course to be understood that I reserve the right to make such changes in the form, construction and arrangement of parts as will not depart from the spirit of the invention or the scope of the subjoined claims.

Having thus described my invention, what I claim and desire to secure by letters patent is:

1. A piston ring provided in its periphery 15 with a continuous oil groove having its upper edge sharp and its lower edge beveled, the lower edge of the ring being sharp and

square and the upper edge being beveled, the ring being formed with a series of holes leading from the groove to the inner 20 periphery.

2. A piston ring provided in its periphery with a continuous oil groove having its upper edge sharp and its lower edge beveled, the lower edge of the ring being sharp 25 and square and the upper edge being beveled, the ring being formed with a series of holes leading from the groove to the inner periphery, in combination with a piston provided with a series of holes leading from 30 the ring receiving groove thereof to the interior.

In testimony whereof I affix my signature.
HERMAN P. WILKE.
